US0D1100213S

(12) **United States Design Patent** (10) **Patent No.:** **US D1,100,213 S**
Blurton et al. (45) **Date of Patent:** **** Oct. 28, 2025**

(54) **PERIANAL SUPPORT DEVICE**(71) Applicant: **STETRIX, INC.**, Bartlett, TN (US)(72) Inventors: **David D. Blurton**, Whiteville, TN (US); **Mark Buchanan**, Atoka, TN (US)(73) Assignee: **Stetrix, Inc.**, Bartlett, TN (US)(***) Term: **15 Years**(21) Appl. No.: **29/852,142**(22) Filed: **Sep. 2, 2022****Related U.S. Application Data**

(63) Continuation of application No. 17/578,951, filed on Jan. 19, 2022, now Pat. No. 11,497,640, which is a continuation of application No. 17/512,244, filed on Oct. 27, 2021.

(51) **LOC (15) Cl.** **24-01**(52) **U.S. Cl.**USPC ..... **D24/190; D24/133**CPC ..... **A61F 5/0093 (2013.01)**(58) **Field of Classification Search**USPC ..... **D24/128, 133, 135, 188-192**CPC **A61F 5/0093; A61F 2007/0028; A61F****2013/15113; A61F 7/12; A61F 2/0009;****A61F 2013/1513; A61F 5/443**

(57)

CLAIM

The ornamental design for a perianal support device as shown and described.

DESCRIPTION

FIG. 1 is a perspective view of a perianal support device showing our new design; and,

FIG. 2 is another perspective view thereof.

The broken lines in FIGS. 1 and 2 illustrate unclaimed portions of the perianal support device and form no part of the design sought to be patented.
